James H. Gabler, Metairie, La., assignor to Kalvar
Corporation, New Orleans, La.

Filed Dec. 22, 1969, Ser. No. 20,607

Term of patent 14 years

Int. Cl. D16—06

U.S. Cl. D61—1

The figure is a left-front perspective view of a printer-processor for vesicular photographic film showing my new design; the right side being a mirror image of the left while the top, rear, and bottom sides are substantially plain and unornamented.

I claim:

The ornamental design for a printer-processor for vesicular photographic film, as shown and described.
